(57) **CLAIM**

The ornamental design for an electronic device, as shown and described.

DESCRIPTION

FIG. 1 is a top, front, and side isometric view of a first embodiment of an electronic device embodying the new design;

FIG. 2 is a bottom, back, and side isometric view thereof;

FIG. 3 is a top view thereof;

FIG. 4 is a bottom view thereof;

FIG. 5 is a first side view thereof;

FIG. 6 is a second side view thereof;

FIG. 7 is a back view thereof;

FIG. 8 is a front view thereof;

FIG. 9 is a cross-sectional view along lines 9-9 in FIG. 3; and

FIG. 10 is a detail view of area 10 in FIG. 9.

FIG. 11 is a top, front, and side isometric view of a second embodiment of an electronic device embodying the new design;

FIG. 12 is a bottom, back, and side isometric view thereof;

FIG. 13 is a top view thereof;

FIG. 14 is a bottom view thereof;

FIG. 15 is a first side view thereof;

FIG. 16 is a second side view thereof;

FIG. 17 is a back view thereof;

FIG. 18 is a front view thereof;

FIG. 19 is a cross-sectional view along lines 19-19 in FIG. 13; and

FIG. 20 is a detail view of area 20 in FIG. 19.

The broken lines showing portions of the electronic device throughout the figures, as well as those indicating cross-sectional and enlarged views in FIGS. 3, 9, 10, 13, 19, and 20, form no part of the claimed design.

In FIGS. 9, 10, 19, and 20, the dash-dot broken lines depicted on interior features of the bottom portion and the top portion of the electronic device define the boundary of the claim, which extends to the boundary, but does not include the boundary lines. Further, the dot-dash broken
